OAR AND PADDLE CONSTRUCTION

Robert Kurtz, Portland, Pa.

Application February 19, 1942, Serial No. 431,593

6 Claims. (Cl. 9—24)

This invention aims to provide a boat propeller of the oar and paddle type, capable of being stowed in small compass, by folding, in a suitcase or the like. The invention aims to improve the stock of the article, and to provide novel means for pivotally connecting the stock with other portions of the device.

It is within the province of the disclosure to improve generally and to enhance the utility of devices of that type to which the present invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

With the understanding that the word "oar" includes paddles and the like, reference may be had to the accompanying drawing, wherein:

Fig. 1 is a top plan of an oar constructed in accordance with the invention;

Fig. 2 is a side elevation;

Fig. 3 is a side elevation wherein the oar is shown folded;

Fig. 4 is a section on the line 4—4 of Fig. 2;

Fig. 5 is a section similar to Fig. 4, but showing a modification;

Fig. 6 is a side elevation of the form depicted in Fig. 5;

Fig. 7 is a top plan showing a further modification;

Fig. 8 is a side elevation showing another modification;

Fig. 9 is an elevation of the blade, parts thereof being broken away, and the stock being removed.

Referring to Figs. 1 to 4 there is shown an oar, generally made of wood, and including a stock 1, comprising a body 2, a grip 3 at the outer end of the body, and a reduced and flattened tongue 4 at the opposite end of the body, the tongue being disposed symmetrically with respect to the central longitudinal axis of the body 2.

Side pieces 5 are disposed on opposite sides of the tongue 4. The numeral 6 marks a blade having a reduced shank 7 extended between the side pieces 5, at the outer ends thereof. The tongue 4 and the shank 7 space the side pieces 5 transversely, to form a longitudinal slot 8, into which the blade 6 can be folded throughout its

length, if desired, and into which the tongue 4 of the body 2 can be folded to a considerable extent.

A means 50 is provided for assembling the blade pivotally with the side pieces 5. In providing the pivot means, bushings 9 are secured in the side pieces 5, the bushings having enlarged sockets 10 at their outer ends. A tubular bushing 11 is secured in the shank 7 of the blade 6. A tubular nut 12 extends through one of the bushings 9, through the bushing 11, and into the opposite bushing 9, the nut 12 having a kerfed head 14 housed in the socket 10 of the first-mentioned bushing. A screw 15 is threaded into the nut 12, and has a kerfed head 16 housed in the corresponding socket 10. It will be noted that the bushings 9 have end abutment against the bushing 11, and, no matter how tightly the screw 15 is set up, the shank 7 of the blade 6 will not be bound so tightly between the side pieces 5 that the blade cannot be folded, as shown in Fig. 3.

A retaining means 51 is employed for holding the blade 6 in the working position of Fig. 2. That means, as shown in Fig. 4, may be a duplicate of the pivoting structure. The retaining means is located between the pivot means 50 and the adjacent ends of the side pieces 5.

The body 2 is pivotally mounted at 52 and is retained at 53. The pivot means and the retaining means for the body 2 may be of the kind hereinbefore described and shown in Fig. 4.

The retaining means shown at 51 and at 53 may be removed, and the blade 6 and the body 2 may be folded into the position shown in Fig. 3. The oar, thus, is shortened to such an extent that it can be carried in a suitcase or stowed in a cupboard.

In connection with the use of some kinds of wood, or if the oar is put away in a wet place, after being folded to the position of Fig. 3, the blade 6, the side pieces 5, or both, may swell and cause the blade to be gripped tightly, it being difficult, under such circumstances to open the blade. In the device forming the subject matter of this application, no such difficulty will be encountered. Referring to Fig. 3, the body 2 may be used as a lever to start the blade 6 from a position in which it may have become stuck.

As indicated in Fig. 1, the shank 7 of the blade 6 has a bushed opening 54, the pivot means 50 being located half way between the opening 54 and the retaining means 51. The blade 6 may be turned end for end, to enter the slot 8 until the longitudinal axis of the blade coincides with the

longitudinal axis of the stock 1. The bushed opening 54 in the shank 7 of the blade 6 thus is brought into registration with the bushings 9 of the side pieces 5, and the retaining means 51 is re-inserted, to hold the blade folded. When 5 the aforesaid method of procedure is resorted to, the body 2 ordinarily is not folded on its pivotal mounting 52.

The retaining means shown at 51 and at 53 must be removed, in order that the blade 6 and the body 2 may be folded as in Fig. 3, and the retaining means may be of any desired form. If preferred, recourse may be had to the structure shown in Figs. 5 and 6. In those figures, parts hereinbefore described have been designated by 15 numerals already used, with the suffix *a*.

In the making of the retaining means in Figs. 5 and 6, a tubular bushing 17 is secured in one of the side pieces 5*a*, that side piece having a superficial, longitudinal recess 18. The bushing 17 is supplied with a flattened, tubular guide 19, seated in the recess 18.

A headed pin 20 extends through the bushings 9*a*, 11*a* and 17, and has a disk-like foot 21, connected to the body portion of the pin by a reduced neck 22. A latch 23 is slidably mounted in the guide 19 and has a rectangular finger piece 24 at its inner end. At its outer end, the latch 23 has a fork 25, adapted to receive the neck 22, beneath the foot 21, thereby to hold the pin 20 against being withdrawn accidentally.

In Fig. 7, parts hereinbefore described have been designated by numerals already used, with the suffix *b*. In this form of the invention, the body 2*b* and the side pieces 5*b* are formed in one piece, the oar having but one fold, namely at the pivotal connection between the blade 6*b* and the side pieces 5*b*.

In Figs. 8 and 9, parts hereinbefore described are designated by numerals already used, with the suffix *c*. The blade 6*c* has an additional bushed opening for the reception of the retaining means 51*c*, located in a common arc with the opening 11*c*. The longitudinal axis of the blade 6*c* is disposed at an obtuse angle to the longitudinal axis of the stock 1, and the blade gets a better hold on the water, especially in the hand of an inexperienced oarsman.

In all forms of the invention the retainers and pivot members enhance resiliency and permit a "snap" not found in a rigid oar, the oar calling for the expenditure of a lessened amount of physical exertion.

Having thus described the invention, what is claimed is:

1. A device of the oar and paddle type, comprising side pieces, a body having one end extended between the side pieces, a blade having one end extended between the side pieces, said ends of the blade and of the body spacing the side pieces to form a slot, the blade and the body being foldable in the slot, pivot means connecting the blade with the side pieces, pivot means connecting the body with the side pieces, movable retaining means connecting the blade with the side pieces, to hold the blade in working position, and movable means connecting the body with the side pieces to hold the body in working position.

2. A device of the oar and paddle type, comprising side pieces, a blade pivotally mounted between the side pieces and foldable to lie between the side pieces, and a body including a hand grip,

the body being pivotally mounted between the side pieces, the relative lengths of the body and the blade being such that the body can engage the blade, when both are folded, and act lever-wise thereon, to start the blade if it is stuck between the side pieces.

3. A device of the oar and paddle type, constructed as set forth in claim 1, and wherein each pivot means comprises an elongated tubular nut, 10 and a screw threaded into the nut.

4. A device of the oar and paddle type, constructed as set forth in claim 1, and wherein one of the pivot means comprises a pin having a foot, the foot being connected to the body portion of the pin by a reduced neck, and a latch slidably mounted on one of the side pieces and forked to span the neck and engage beneath the foot.

5. A device of the oar and paddle type, comprising a stock including side pieces defining a slot in one end of the stock, the side pieces having inner and outer openings disposed in a straight line extended lengthwise of the stock, a blade extended into the slot and having inner, outer and intermediate openings, the outer and intermediate openings of the blade registering, respectively, with the outer and inner openings of the side pieces, the blade being provided with a lateral opening disposed, together with the outer opening of the blade, in an arc whereof the intermediate opening of the blade is a center, a pivot means disposed in the inner openings of the side pieces and in the intermediate opening of the blade, and a retaining means removably mounted in the outer openings of the side pieces and of the blade, to hold the blade in working position and in axial alignment with the stock, the blade being movable on the pivot means, when the retaining means is removed, to bring the lateral opening into registration with the outer openings of the side pieces, the retaining means being insertible into the last-specified openings of the blade and of the side pieces, to hold the blade at an obtuse angle to the stock, the blade being capable of end-for-end reversal on the pivot means, to locate the blade in the slot, when the retaining means is removed, and to bring the inner opening of the blade into registration with the outer openings of the side pieces, for the reception of the retaining means.

6. A device of the oar and paddle type, comprising a stock including side pieces defining a slot in one end of the stock, the side pieces having inner and outer openings disposed in a straight line extended lengthwise of the stock, a blade extended into the slot and having inner, outer and intermediate openings, the outer and intermediate openings of the blade registering, respectively, with the outer and inner openings of the side pieces, a pivot means disposed in the inner openings of the side pieces and in the intermediate opening of the blade, and a retaining means removably mounted in the outer openings of the side pieces and of the blade, to hold the blade in working position and in axial alignment with the stock, the blade being capable of end-for-end reversal on the pivot means, to locate the blade in the slot, when the retaining means is removed, and to bring the inner opening of the blade into registration with the outer openings of the side pieces, for the reception of the retaining means.
